UNITED STATES PATENT OFFICE.

ZEPH WIGGS, OF DENTON, TEXAS, ASSIGNOR TO JAMES E. HENDERSON, OF DENTON, TEXAS.

SHAFT-TUG.

SPECIFICATION forming part of Letters Patent No. 723,222, dated March 17, 1903.

Application filed December 27, 1900. Renewed July 8, 1902. Serial No. 114,824. (Model.)

To all whom it may concern:

Be it known that I, ZEPH WIGGS, a citizen of the United States, residing at Denton, in the county of Denton and State of Texas, have 5 invented a new and useful Shaft-Tug, of which the following is a specification.

This invention relates to a shaft tug or support; and the object of the same is to provide simple and effective means whereby a 10 shaft may be readily inserted in or removed from the top portion of the tug or support instead of by threading the shaft through the latter.

The invention consists in the construction 15 and arrangement of the several parts, which will be more fully hereinafter described and claimed.

In the drawings, Figure 1 is a perspective view of the improved device, showing a portion 20 of a thill applied thereto. Fig. 2 is a side elevation of the improved device shown open. Fig. 3 is a transverse vertical section of the improved device. Fig. 4 is an enlarged transverse section through a portion 25 of the bow of the device and the closing-jaw therefor, showing the hinge-joint and locking means.

Similar numerals of reference are employed 30 to indicate corresponding parts in the several views.

The numeral 1 designates the usual saddle-strap, which is adjustably connected to a buckle or other similar device 2, attached to the upper inner terminal of the main body 35 portion or bow 3 of the tug or loop. This body portion or bow 3 is composed of a metallic band 4, which is bent into a curve slightly greater than a semicircle and has the inner terminal extending above the outer terminal. The body portion or bow is of the 40 same dimension as the ordinary form of tug or loop, and the band 4 is provided with a suitable covering 5, of leather or the like, to prevent scoring or rubbing the thill, and the outer terminal of the said band is formed 45 with a central knuckle 6, having an inner shouldered recess 7. The outer end of a closing-jaw 8 is formed with spaced knuckles 9 to complete a hinge-joint with the knuckle 50 6 by the addition of a pintle 10. The jaw 8 is constructed of suitable metal and con-

veded and has an inner upturned terminal 11 to snugly bear against the outer side of the inner terminal of the body portion or bow 3. On the upper portion of the jaw 8 a curved 55 latch 12 is movably mounted and has an elongated slot 13 therein through which a combined guide and retaining stud 14 projects and has a flanged head 15. The inner terminal of the latch is upturned, as at 16, and between said terminal and an inner upstanding guard 17 a coiled spring 18 is mounted and terminally secured, the said spring operating to force the latch outwardly into locking position. The outer end 19 of the latch is suitably reduced to engage the shouldered recess 60 7 of the knuckle 6, the width of the latch being about equal to the length of the knuckle 6, and the latter being stationary the lock of the jaw will be effected through the said jaw 70 only.

In applying a thill to the improved tug or loop the latch 12 is drawn or pushed inward to release the jaw 8 and the latter opened to clear the upper portion of the body or bow 3. 75 The thill is then lowered into the body or bow and the jaw closed and automatically locked against accidental disengagement by the latch. The thill can be readily released from the tug or loop by opening the jaw. The use 80 of the improved device will obviate breaking or twisting the thills or shafts and materially hasten the operations of hitching and unhitching an animal and being of a simple nature can be easily operated and cheaply 85 manufactured. Moreover, the several parts are strong and durable and will form a material addition to the general convenient equipments of harness.

Having thus described the invention, what 90 is claimed as new is—

A shaft-tug, comprising a body-bow having a vertically-extending attaching member projecting above the outer end of the bow, the said outer end having an integral knuckle 95 provided on its inner face with a shoulder, a jaw having a curved inner terminal to bear against the attaching member and its outer terminal provided with knuckles pivotally secured to the knuckle of the bow, and a 100 spring-actuated latch carried by the upper side of the jaw and having its outer end dis-

posed to engage the shoulder to lock the jaw in position, and at its inner end an upturned lug which affords an abutment for the spring and a convenient operating means for the latch, substantially as and for the purpose specified.

In testimony that I claim the foregoing as

my own I have hereto affixed my signature in the presence of two witnesses.

ZEPH WIGGS.
